ATTORNEY

UNITED STATES PATENT OFFICE.

GEORGE J. NETTER, SR., OF INDEPENDENCE, MISSOURI.

LOOSE-LEAF BOOK.

Application filed July 2, 1927. Serial No. 203,187.

My invention relates to note book binders and has for its principal objects reduction in expense of manufacture of loose leaf note books, production with a small number of parts, improvement in binding mechanism whereby a binder may be conveniently re-filled or leaves removed, and provision of a rigid back and flexible front cover.

In accomplishing these objects I have provided improved details of structure, the preferred forms of which are illustrated in the accompanying drawings, wherein:

Fig. 1 is a perspective view of a note book binder, filled, and in closed position.

Fig. 2 is a perspective view of a binder in open position.

Fig. 3 shows the back member and the cover member separated, and fragmentarily.

Fig. 4 is a vertical cross section of the device on the line 4—4, Fig. 5.

Fig. 5 is a fragmentary longitudinal section on the line 5—5, Fig. 1.

Referring in detail to the drawings:

1 designates a note book binder such as 25 fully illustrated in Fig. 2, designed to hold sheets 2, and comprising a back or back cover member 3 and a front cover 4 fixed to a hinge member 5. The means of associating the cover or hinge with the back represents important features of my invention.

The back 3 is preferably constructed of metal, binding posts 6 being upstruck adjacent one end and formed as indicated by 7 and particularly illustrated in Fig. 4, to provide cylindrical pins or posts to receive the sheets 2, which may be the usual type of perforated sheets of a note book, or printed pages, or any objects for which a binder or support may be desired. Ears or flanges 8 are provided for in the metal sheet from which the back is made, and upturned from the back, so that they preferably stand in alignment with the edges of the back member, and are provided with bearing or journal openings 9, and with externally produced latch-receiving recesses or sockets 10. The back 3 is also upturned in curved form at its end to provide an arcuate sleeve or channel portion 11, the flanges being 50 formed in outline to the curvature of the channel portion. The openings 9, sockets 10 and curved end 11 are adapted for co-operation with the hinge member 5, which is also preferably made of metal, having

55 downturned ears 12 in which journal members 13 are provided either as separate mem-

bers or as bosses, the latching bosses 14, and the curved portion 15. The journals 13 are adapted to fit into the journal openings of the flanges of the back member 3, to pivot the hinge member to the back, and may consist of eyelets having hubs for hinging. The latching bosses are positioned to engage in the recesses 10 to latch the hinge member in closed position. The curved portion 15 of the hinge member is adapted to engage and slide over the curved portion of the back, to provide supporting and strengthening factors thereby, to eliminate rough corners, and to improve the appearance of the device.

Another particular feature of the device resides in a flexible cover member 16, of leather or composition material, secured to the hinge member by means such as tangs 75 17 struck from the hinge member.

The hinge member is also a retaining member, which is swung away from the back to permit insertion of leaves, and is swung and latched in closed position to retain the 80 leaves. The hinge member extends over the posts 6, and contacts with them when it is in closed position. The flexible cover may then be raised, for disclosing the leaves of the book, without disturbing the retaining member, the process being simpler and more convenient than the opening of a hinged cover. The leaves are held firmly by the posts and retaining member in established 85 relation to each other and to the back, and a small number of leaves may be securely retained.

The resilient flanges and resilient ears provide effective latching means, easily operated, substantial and not likely to get out 90 of order.

A sturdy binding or cover device is therefore produced, having few parts, not subject to disrepair, easily operated and efficiently retaining the contents for convenient access. The device may be applied to other purposes than that of a loose leaf note book, with which the structure is here preferably illustrated.

What I claim and desire to secure by Letters Patent is:

1. In a binder, a back member having an upwardly curved end and upturned flanges adjacent said end, posts positioned on the back member adjacent said curved end, and a retaining member having a portion curved for sliding engagement with said curved end

of the back member and portions pivotally connected with said flanges of the back member.

2. In a device of the class described, a back member having an upwardly curved end and upturned ears adjacent said end, posts positioned on the body member adjacent said curved end, a hinge member having a portion curved for sliding engagement with said curved end of the body member and portions hinged to said ears, and a flexible cover secured to said hinge member.

3. In a device of the class described, a backing member having resilient ears at one end provided with latch-receiving recesses, posts secured to the backing member, and a retaining member pivotally mounted on the backing member and provided with latching bosses to be received by said recesses of the backing member.

4. In a note book device for perforated

sheets, a back cover member having side flanges at one end provided with latch-receiving recesses and journal openings, posts secured to the back cover member to receive perforated sheets, and a retaining member having ears provided with spindles journaled in said flanges, said ears also being provided with latching bosses to be received by said recesses of the back cover member.

5. In a note book device for perforated sheets, a back cover member having side flanges at one end provided with latch-receiving recesses, posts secured to the back cover member to receive perforated sheets, a hinge member having ears pivotally mounted in said flanges and provided with latching bosses to be received by said recesses of the flanges, and a flexible front cover member secured to said hinge member.

In testimony whereof I affix my signature

GEORGE J. NETTER, Sr.
